UNITED STATES PATENT OFFICE.

CHARLES A. CARLSON, OF EVERETT, NEW JERSEY.

PLOW.

1,192,388.

Specification of Letters Patent. Patented July 25, 1916.

Application filed April 22, 1914. Serial No. 833,607.

To all whom it may concern:

Be it known that I, CHARLES A. CARLSON, a citizen of the United States of America, and a resident of Everett, Monmouth county, and State of New Jersey, have invented certain new and useful Improvements in Plows, of which the following is a specification, reference being had to the accompanying drawings, forming a part thereof.

10 My invention relates to plows and especially to those which are supported upon a motor-driven vehicle, and its object is to provide a simple and inexpensive apparatus which has advantages over such arrangements as have been available heretofore.

In order that my invention may be thoroughly understood, I will now proceed to describe the same in the following specification and then point out the novel features 20 thereof in the appended claim.

Referring to the drawings: Figure 1 is a side elevation of a power plow. Fig. 2 is a sectional side elevation of the same apparatus. Fig. 3 is a plan view partly in section of 25 the power plow shown in the preceding figures. Fig. 4 is an end elevation partly in section, on a larger scale of the vehicle and a part of its driving mechanism. Fig. 5 is an end elevation of a part of the driving mechanism showing in detail a part of the reversing 30 mechanism.

Like characters of reference designate corresponding parts in all the figures.

10 designates the frame of the vehicle 35 which has near its opposite ends two turntables or "fifth wheels" 11 each of which rests upon and removably supports an axle 12. Near the ends of these axles on one side of the vehicle frame are shackles 13 which 40 are connected by chains or cables 14—15, with a drum 16 affixed to a transverse shaft 17 about which they are wrapped in opposite directions, and to which they are affixed. Near the opposite ends of the axles 45 are shackles 13^A and chains or cables 14^A—15^A which are wrapped about a drum 16^A on shaft 17. Hand wheels 18 afford means for rotating the shaft 17 and its drums 16 and 16^A, and the parts are so arranged 50 that this rotation in one direction hauls in the ropes or cables on one side of the vehicle and pays out those on the opposite side, resulting in turning the two axles in opposite directions relatively to the vehicle frame. In this manner the vehicle is steered or guided.

Through the center of each axle is a shaft 20 near the center of which are affixed two bevel gears 21 and 22. The vehicle wheels 23 are mounted to rotate on the axles and 60 are provided with driving connections 24 with shaft 20 in the usual manner.

25 are bevel driving gears, one of which is mounted in an eccentric bearing 26 in the inner central portion of each of the axles 12. 65 These two eccentric bearings may be turned simultaneously by segmental gears 27 and suitable connecting rods and levers 28, from a hand lever 29 at one side of the vehicle midway between its ends. 70

The driving gears 25 will be driven in one direction by the motor. When the lever 29 is thrown in one direction the gear 25, near one end of the vehicle, will be thrown into mesh with its corresponding gear 21 and 75 will cause its shaft 20 and wheels 23 to be rotated in one direction. At the same time the gear 25 near the other end of the vehicle will be thrown into mesh with its corresponding gear 22 to cause rotation of the 80 other vehicle wheels. Consequently, all of the vehicle wheels are driven positively and obviously the direction of drive may be reversed by throwing lever 29 in the opposite direction. 85

An internal combustion motor 30 is located in the center of the vehicle and is shown in outline in Figs. 2 and 3 of the drawings with its tank and accessories omitted as these form no part of this invention and may be located in any convenient part of the vehicle. A small gear 31 on the engine shaft is in mesh with a larger gear 32 loosely mounted on a longitudinal shaft 33 below the motor. This larger gear 95 is affixed to one member 34 of a friction clutch the other member of which, designated by 35 is splined to the shaft 33 and is arranged to be thrown into engagement with the clutch member 34 by a hand lever 36 to 100 effect a driving engagement between the engine and the shaft 33.

The driving gears 25 are connected with the shaft 33 by connecting shafts 37 at either end of each of which are universal joints 38 which provide the desired amount of flexibility for the throw of the eccentric bearings 26 and for the turning movement of the axles 12. As the latter movement changes the distance between the shaft 33 and the 110 gears 25, slightly, the connecting shafts 37 are made of two telescoping members which

are arranged to turn together and to have the required amount of relative longitudinal movement.

The parts which I have described form a self-propelled, reversible and dirigible vehicle which obviously is useful for many farm and other purposes as it may be used as a tractor or a truck. But the specific object of this invention is to provide a 10 double ended reversible plow which may be done by attaching the parts which now will be described.

Each of the plow attachments comprises a frame 40 which may be bolted to the vehicle frame 10 and on which are mounted downwardly projecting supports such as 41. Near the lower end of each of these supports is a vertical row of holes 42 in any one of which a pin may be inserted to pivotally 20 support a plow beam 43 on the other end of which is a plow-share 44 which is pointed toward the transverse central plane of the vehicle. On the frame 40 is a bearing block 45 in which is pivoted a bell-crank lever 46. 25 47 is a connecting rod between one arm of this bell crank lever and the plow beam 43. One of these bell crank levers is connected by a rod 48 with a hand lever 49 near the center of the vehicle, by means of which the 30 plows at one end of the vehicle may be raised or lowered. The other bell crank lever 46 is connected by a rod 50 with a hand lever 51 so that the plows at the other end may be raised or lowered. The hand 35 levers 49 and 51 are mounted to swing on a common center 52 with a sector 53, the periphery of which is notched to receive locking pawls on the hand levers. The sector itself may be swung about the center 52 40 by a handle 54 which obviously raises the plows at one end of the vehicle and simultaneously lowers those at the other end.

By reference to Fig. 3 it may be seen that the frames 40 are each adapted and ar-

ranged to carry a gang of plows, two being 45 shown at each end of the vehicle.

In operating this device the operator is seated in the center of the vehicle where all of the steering and controlling devices are within easy reach. After running the length 50 of a field and plowing as many furrows as there are plows at the end of the vehicle, the vehicle is stopped, the plows which have been dragged are lifted, and those at the other end of the vehicle are lowered. Then 55 the vehicle is run in the opposite direction along a path parallel to that which it had previously traversed. Thus there is no necessity of turning the apparatus around which is generally an awkward and time-consuming operation. Moreover, with this device the field may be plowed much closer to the line fences or walls than is possible with such apparatus of this type as has been 60 available hitherto.

I have shown an embodiment of my invention in more or less diagrammatic form as it may be embodied in structures of widely different design, and I intend no limitations other than those imposed in the 70 appended claim.

What I claim is:

A reversible vehicle, a plow at each end of the vehicle, both of said plows being pointed toward the central transverse plane 75 of the vehicle, means for simultaneously raising the plow at one end of the vehicle and lowering the plow at the other end thereof and other means for independently adjusting the vertical position of either of 80 the plows.

In witness whereof, I have hereunto set my hand in the presence of two subscribing witnesses, this 20th day of April, 1914.

CHARLES A. CARLSON.
